UNITED STATES PATENT OFFICE

WILLIAM G. WILSON, GEORGE S. DARLING, AND HENRY WULFF, OF CHICAGO, ILLINOIS, ASSIGNEES TO WILSON SEWING MACHINE COMPANY, OF SAME PLACE.

SEWING-MACHINE.

SPECIFICATION forming part of Letters Patent No. 241,770, dated May 17, 1881.

Application filed August 17, 1880. (Model.)

To all whom it may concern:

Be it known that we, WILLIAM G. WILSON, GEORGE S. DARLING, and HENRY WULFF, of Chicago, in the county of Cook and State of Illinois, have invented a new and useful Improvement in Sewing-Machines, of which the following is a specification.

Our improvements relate to sewing-machines of the class using oscillating shuttles; and it consists in certain novel features of construction, hereinafter more fully set forth and claimed.

In the drawings, Figure 1 is a sectional side elevation of the improved machine. Fig. 2 is an inverted plan view, showing the mechanism beneath the bed. Fig. 3 is a rear view of the face-plate carrying the needle-bar. Fig. 4 is a horizontal section of the face-plate on line *y y* of Fig. 3. Fig. 5 is a longitudinal section of the shuttle. Fig. 6 is a perspective view of the same. Fig. 7 is an end view of the machine, showing the hand-wheel and clutch, and also the bobbin-winder; and Fig. 8 is a partial section of the arm, showing the mechanism for revolving the feed-shaft and oscillating the shuttle.

Similar letters of reference indicate corresponding parts.

A is the bed; *B*, the arm above the bed. *a* is the driving-shaft, carrying hand-wheel *b* and needle-bar crank *c*. *d* is the needle-bar. *e* is the shuttle-carrier contained in case *C* and attached on the end of shaft *f*. *g* is the shuttle, and *k* is the feed-bar.

The needle-bar *d* extends through apertures in the face-plate *a'*, and is carried by the cam *h*, with which the crank-pin of crank *c* engages. The ends of cam *h*, as shown most clearly in Fig. 3, move on guides *h'* *h''*, that are formed at the inner side of face-plate *a'*. One end of cam *h* (see Fig. 4) is fitted with a steel plate, *i*, which rests on the guide *h'*, and with a screw, *i'*, which bears on plate *i*, so that by moving the screw *i'* the cam is adjusted laterally with reference to the guides.

By our construction, as described, wherein the needle-bar is fitted within the face-plate and the adjustment made by the cam, we are enabled to use a round needle-bar, which is best and cheapest, and perfect adjustment can

be made for taking up lost motion by wear or otherwise.

The casting forming the case *C* of the shuttle-carrier is formed with side lugs, *g'*, which are slotted vertically for receiving the feed-bar *k*. In one lug, *g'*, is a pin, *g''*, that passes through the slotted end of the feed-bar.

The feed-operating shaft *l*, fitted beneath bed *A*, is provided with a cam, *l'*, beneath bar *k*, and with a second tapering cam, *l''*, which is at the side of an extension, *l'*, from bar *k*, that carries a friction-roller bearing on cam *l''*. A spiral spring, *m*, connected to case *C* and bar *k*, serves to give the backward and downward movements to the feed-bar and preserve the contact with the cams. The cam *l'* acts to swing bar *k* upward on the pin *g''*, while cam *l''* gives the forward-feed movement.

Beneath the bed is a rod, *n*, which is fitted parallel with shaft *l*, and carries a forked arm, *m'*, that engages with an annular slot in cam *l''*. The outer bearing of rod *n* is provided with a finger-nut, *n'*, into which a screw-threaded portion of rod *n* passes. The cam *l''* is held on shaft *l* by a groove and feather, so that the cam may move endwise of the shaft. By this construction nut *n'* may be turned, and rod *n* thus moved endwise to move cam *l''* and bring any portion of its inclined surface against the friction-roller *k''*, mounted in the arm *l'* of feed-bar *k*. The length of feed-movement is thus adjusted as required. The shaft *l* is rotated by a connecting-rod, *o*, from an eccentric on shaft *a*, and the shaft of the shuttle-driver is rocked by connections from rod *o*, as shown in Fig. 8, and next described.

At the inner side of arm *B* is fixed a block, *p*, having a vertical slot in which moves a fulcrum-roller, *o'*, of the pitman *o*. The roller *o'* is carried by a pin, *q*, that passes through the hub of a short pitman, *q'*, and through the pitman *o*. The short pitman *q'* connects with a crank-arm, *f'*, of shaft *f*, and by properly proportioning the cranks shaft *f* is rocked by the connections. In order to allow working as close to the crank-centers as possible without passing, and to permit adjustment for variations in length of crank *f'*, the pin *q* is formed with an eccentric shoulder, *p'*, on that portion passing through the long pitman *o*, and the

pin is held from turning by a set-screw through the front of pitman o . By turning pin q the crank f' is raised and lowered as may be required.

- 5 The hand-wheel b is to be driven by a belt in the usual manner. This wheel is held loosely on shaft a , between arm B and a collar, b' , that is attached on the shaft. The collar b' carries a clutch-arm, r , that binds against an inner 10 shoulder on wheel b when the latter turns in one direction, so that the wheel and shaft turn together, but permits independent revolution of the wheel in a contrary direction.

The bobbin-winder consists of an arm, s , 15 hung in a box, s' , that is attached on the rear of arm B , and carrying spindle t for the bobbin and roller t' , that comes in contact with wheel b when arm s is turned outward. The hinge-pin of arm s , in the box s' , is provided 20 with a spiral spring that tends to draw the arm upward and engage the pin s^2 with a slot in box s' when the arm is turned outward, so that the roller is held in contact with wheel b and the arm held rigidly. To turn back the 25 arm it is first drawn down to disengage pin s^2 . The loose wheel b , in connection with the bobbin-winder, placed as described, constitutes a convenient arrangement, as the bobbin can be wound without operating the shaft a .

- 30 The shuttle g , as shown in Figs. 5 and 6, is formed with a main cavity that receives the loose bobbin u , and a smaller cavity, v , near the point, in which the tension devices w are placed.

The partition w' , separating the two cavities, 35 is formed with a slot, through which the thread passes from the bobbin to the tension. The bobbin-cavity is fitted with a plate, u' , forming a cap or covering that sets within the rabbeted edges of the cavity, and is formed with a lip, 40 u^2 , that extends over the thread-slot. This cap u' is attached by a pin, v' , around which is a spiral spring in a cavity of the shuttle, so that the spring tends to draw the cap down to place, and also permits the cap to be drawn up

and turned outward for insertion and removal 45 of the bobbin.

The shuttle-tension devices w consist of circular disks upon an internally screw-threaded sleeve that is fitted on a screw-stud with a spiral spring beneath the lower disk, so that 50 by turning the screw-sleeve the spring shall press the disks together with more or less tension.

Having thus described our invention, what we claim as new, and desire to secure by Let- 55 ters Patent, is—

1. In a sewing-machine, the combination, with needle-bar d and face-plate a' , provided with guides h' , of cam h , carrying the needle-bar plate i , resting on one of the guides h' , and 60 means for adjusting said plate i relatively to said guide h' , substantially as described.

2. In sewing-machines, the combination of cam h , plate i , and screw i' with needle-bar d , plate a' , and guides h' , substantially as and for 65 the purposes set forth.

3. The combination, with the feed-operating shaft l and tapering cam l' , fitted to slide thereon, of screw-rod n , having fork m' , and nut n' , and feed-bar $k k'$, carrying the frictional roller 70 k'' , substantially as and for the purposes set forth.

4. In sewing-machines, the combination, with the reciprocating pitman o of the feed-shaft, and short pitman q' , that is connected with the 75 crank of the shuttle-driving shaft, of slotted block p , and fulcrum-pin q , formed with eccentric shoulder p' , and carrying roller o' , substantially as and for the purposes set forth.

The above specification of our invention 80 signed by us this 15th day of July, 1880.
